(54) **THRASHING MACHINE**

(76) Inventor: **Washington F. Pagett**

Washington G. Payett
Letters Patent

The schedule referred to in these Letters Patent and making part of the same containing a description in the words of the said Washington G. Payett himself of his improvement in the Threshing Machine.

To all to whom these presents shall come. Be it known that I, Washington G. Payett of White Post in the County of Frederick and State of Virginia have invented a new and usefull improvement in the Threshing Machine and that the following is a full clear and exact description of the construction and operation of the said machine as invented or improved by me. The concave bed is one of the parts to which I apply my improvement and this I construct in the following manner. It is to be formed into the usual portion of the circumference of the cylinder say from about eight to ten inches and armed with the teeth in the like manner. Also place it on the upper portion of the cylinder above the centre instead of below as is commonly used. It is securely fastened at that part of the cylinder over which it is to work to a moveable frame which is to consist of a broad piece of about fifteen inches in breadth by about three on the edge, and about two and a half feet in length, one piece to be secured to each end of the concave bed where such a portion of the edge at the top of the piece is to be removed as will admit the concave. As the frame is to be used at one end of the machine in a vertical position the cylinder of course is placed at that end & the frame will be placed at a proper distance in front of it. From the bottom of the concave these pieces are framed into a curve so as to keep clear of the cylinder and at about twenty inches below the concave, a broad flat slide board is framed in to slope from the side of the curve next to the cylinder towards the outside of the machine directing the grain which falls on it towards the bottom, or the floor. From the outer edge of this slide board a broad piece follows the curve of the cylinder towards the under part thereof for a short distance where it laps over

to the top of a long slide board which conducts the stone beneath the cylinder to the other end of the frame of the machine & this broad piece protects the springs beneath from dirt &c. Below this broad piece last mentioned and at the bottom of each end piece of the moveable frame is to be an arrangement to allow of a receding motion of the concave in case of the passage of a stone &c. thus a small friction roller is made to project below the piece somewhere near the centre upon which the end of a spring, is to bear & which spring is to be continued horizontally beneath the long slide board from the friction roller towards the other end of the machine frame as may be necessary. The shape of that end of the spring which bears against the friction roller is triangular having one side attached to the spring & the angular edge to be opposed to the roller, thereby forming an inclined plane over which it rides on the front & falls on the back side thereof whenever the accidental passage of a stone or other body causes the concave bed to yield from the cylinder. When the roller passes over the angle a jerkstone is necessary to be applied to the concave bed to send it to its place again. I also apply another mode of effecting the same end of allowing the ~~concave~~ to recede thus. A long arm is deemed at the bottom of each end piece to be continued under the long slide board in the same direction as the spring & from one to the other of which at the end ~~furnished~~ from the frame is to extend a broad piece or box for the reception of as much weight as may be found necessary to carry the box back again to its place after having yielded to the stone &c. & which must be sufficient to keep it to its place during the operation of threshing. This mode may be used instead of the spring, and I think it preferable. Between the first described slide board and the concave a grate is to be used consisting of bent rods placed vertically, but following the general curve of the moveable frame & cylinder for the passage of the grain in front of the ~~me~~ and in front of this grates an iron shaft is to pass through the end pieces forming the sides of this frame attached to the concave and securely keyed to them, having the ends of said shaft to project sufficiently beyond the said side pieces of this frame to equal the length of the cylinder shaft & to rest upon blocks on which they will rock (as the concave recedes) placed on the same support

in proportion to the cylinder. And that shaft must be placed so as to have the centre of the distance between the concave bed and the ends of the side pieces where the friction rollers are placed so to give sufficient leverage when accommodated to the strength of the springs (or the weight) as to bring the bed to its place after the stone &c has passed. The stone or base of which the cylinder is composed. I secure to the heads by means of screws placing the stones above the head. and I place secret nuts between the bands & the head or by screwing the bolts into the band. which is intended to give more facility to remove by unscrewing the stone and removing it without having to move the bands. The main cylinder shaft is to revolve on a box of metal at each end as is usual but to one of these boxes I adapt the following improved construction viz. The round end of the shaft is to have a groove turned in it near about the centre (& the lower box on my drawings) have a corresponding rise to fit into it resting upon the lower bush; over this I place a cap thus three formed. The hollow is adapted to the size of the end of the shaft & on each side of it a portion somewhat wider than the groove in the axle is removed to a sufficient distance from the hollow to allow of the reception of a square piece calculated to fit into it but somewhat narrower that it may slide both backward or forward across the opening when required. The end of this square block that is to bear upon the round end of the shaft is shaped to fit it in the same curve as the hollow and has one of the vertical sides (or length of the box) to project in a thin ^{plate} sufficiently forward or into the hollow to bear on to the bottom of the groove and the side of this projection is to bear against the square side of the groove. The square piece on the other side of the hollow in the cap will have the same shape & projection. but the last will be on the opposite side of said square piece. Through these pieces a screw bolt is to pass near the centre of each. the thread of which is removed at each end thereof & a head is secured at one. & a rivet at the other or any such fastening for a similar intent viz of rendering the screw stationary or not to be withdrawn from this place. The use of this screw is to carry forward or backward the square piece cut with a female screw when the bolt is turned in order to press against the side of the

the groove & thereby keep the shaft steady. The projecting ends of these pieces may be made of hard metal and movable so as to renew them when necessary. It is admitted through a hole at the top. I also propose another mode of operating the spring by means of an extension of the inclining plane at the triangular end by which the front side thereof is carried upwards from the angular edge into a curve forming part of a small circle there would be described by the friction roller as the beam recedes, so that the roller not passing the point but running up the curve the resistance of the spring would bring it back again after the stone be has passed. Operation. The square shaft with a concave end forming a pivot on which the moveable frame can swing should any stone be driven by the cylinder into the concave, it will yield or recede outwards by means of the revolutions of the friction roller over the front inclined, the resistance of the spring against which sends it back again should the stone be small, but should it be large the roller may pass the point of the angle & then the concave will be required to be thrust back to the beam, but if the curve is made at the top of the plane the roller does not need any assistance but is driven down by the resistance of the spring given the application of the lever & weight the concave equally is brought against the cylinder by the leverage obtained by the length of the frame below the pivot shaft. Having the upper cap to any shaft requiring to be occasionally tightened. The heads of the screw bolts are turned which as they have threads only within the portion removed on each side the hollow & passing through the regulating square pieces, these pieces will be driven closer to the square side of the groove on opposite sides thereof which will consequently hold the angle steady, again when previously worn by friction. What I claim as my invention and not previously known in the above described machine is First. The arrangement of the spring and friction roller as described at the bottom of the moveable frame to allow of the receding motion of the concave. & also the other construction for obtaining the same end by means of the long arms and top or broad piece to apply a weight for the purpose. 2dly. The manner or method of constructing the cap as described for the purpose of adjusting the position of

United States Patent

Patent No.: X8837

of the main shaft or any other shaft. In testimony that the above is a full and exact description of the construction and modes of operation of my machine as invented or improved by me I have hereunto set my hand this twenty seventh day of April eighteen hundred and thirty six
